CATHODE RAY TUBE SCREEN

Max Knoll, Bernhard Bartels, and Otto Spengler,
 Berlin, Germany, assignors to Telefunken Ge-
 sellschaft für Drahtlose Telegraphie m. b. H.,
 Berlin, Germany, a corporation of Germany

Application April 19, 1937, Serial No. 137,599½
 In Germany March 19, 1936

4 Claims. (Cl. 250—150)

This invention relates to electric signalling, and in particular, to facsimile and television transmission systems utilizing cathode ray scanning means.

5 This invention is an improvement upon the method and means for electric signalling disclosed in my co-pending application Serial No. 106,301, filed October 19, 1936 by Fritz Schröter and Max Knoll, and entitled "Transmitter system", and now Patent Number 2,156,435.

In certain types of transmission, it is desirable to scan a still picture or sign either for testing advertising or identification purposes. For example, in a television transmitting station, it is desirable at the end of a program to identify the station transmitting the television program. This identification might comprise the call letters of the station and include some symbol used as a trademark or identification sign by the station. Such a symbol or picture, as well as the call letters, may well be a half-tone picture. Instead of using the studio scanner for scanning the picture surface for this short in accordance with the invention disclosed in the above identified application, this invention teaches the use of a special scanner which makes use of the different secondary emission properties of two or more materials. According to the present invention, a supporting surface for the picture to be transmitted is made of one material, while the picture proper is made of another material and supported on the surface of the plate. A cathode ray scans the picture area and depending upon whether the ray impinges on an elemental area of the support, or upon an elemental area of the picture proper, more or less secondary electrons will be released in accordance with the secondary emission properties, which characterizes the supporting surface or the elements of the picture proper. An electrode serves to capture the released secondary electrons and these electrons serve in turn to produce a voltage representative of the elemental area scanned, which voltage is then amplified by a conventional means and appropriately transmitted.

Accordingly, it is one of the objects of our invention to provide an improved method and means for transmitting electro-optical effects.

Another object of our invention is to provide an improved method and means of transmitting half-tone pictures.

A still further object of our invention is to provide an improved screen picture transmitting plate for use in a cathode ray tube scanner.

55 Other and ancillary objects will appear upon

reading the description together with the claims, in which

Fig. 1 shows schematically a cathode ray scanning system for use with the plate prepared in accordance with our invention, and

Fig. 2 shows a cross-section of a half-tone plate prepared according to our invention.

Referring now to the drawing, in Fig. 1 a cathode ray tube 10 is shown comprising a glass bulb designed partially as and with the shape 10 of a cylinder, attached to which is a frustum of a cone. Within the cylindrical portion of the glass bulb a cathode 11 and electrode 22 are shown conventionally connected with a battery 23 to provide an electron gun for concentrating 15 and accelerating the electrons to provide a beam of high speed electrons. Two pairs of deflecting plates 12 and 13 are arranged at right angles to each other for purposes of deflecting the beam of electrons generated within the electron gun 20 so that the beam traverses a predetermined pattern of scanning. These electrodes may, for example, be supported by the wall structure of the tube 10 or as is more usual, be supported from the gun structure as is well known in the prior 25 art. A metal electrode 14 is positioned in the frustum portion of the tube 10 intermediate the deflecting plates 13 and the half-tone plate 15. Connected between the plate 15 and the electrode 14 is a battery 16 in series with a re- 30 sistance 17 to which are connected the terminals 18. The cathode ray beam scanning the plate 15 causes secondary electrons to be ejected therefrom due to the velocity of impact upon the plate 35 and these secondary electrons are collected by the electrode 14 and current flow in accordance with the electrons reflected through the resistance 17, which gives rise to signal voltage for transmitting the electro-optical effects.

Fig. 2 shows in cross sectional view, the plate 40 15. The plate 15 may be made of metal, such as aluminum, for example, upon which the half-tone image is arranged in accordance with the half-tone screening methods and further, differs in this respect from the invention disclosed 45 in the above identified copending application of Schröter and Knoll, in that the co-pending application provides a plate which is photo-electrically engraved or recessed, the recesses being filled with carbon or some other material having 50 a different secondary emission characteristic than the supporting plate 15.

As will be appreciated, photo-engraving processes require considerable care to be taken, and are, relatively speaking, a complicated process. 55

Applicants, therefore, have done away with the necessity of using a photographically etched plate by providing a plate upon which the picture proper is disposed upon the supporting metal plate. In general, the process consists in coating the smooth surface of the plate with a photo-chemical substance. By "photo-chemical substance" is meant a substance whose chemical and physical properties undergo changes when exposed to light. And for this purpose, applicants may utilize a coating of chrome gelatin, which comprises gelatin in which has been included potassium bi-chromate. Such a gelatin is soft and pliable, but upon exposure to light, the area of the chrome gelatin so exposed, hardens. Thereafter, if the layer is washed in water, the unexposed portions are washed away, leaving in relief the portions of the film which have been exposed to light which are insoluble. The changed chrome gelatin remaining upon the layer has secondary emission properties which are not greatly different from carbon, and consequently, differs appreciably from the secondary emission properties of the metallic plate supporting the film of chrome gelatin. Thus, to prepare the plate, it is merely necessary to flow the chrome gelatin upon the polished surface of the plate in the dark, exposing the plate to the picture of which representation is desired, by projecting the picture upon the plate and through a half-tone screen where the picture is different from a black and white picture, to provide the half-tone screening details. Thereafter, the plate is rinsed in water and the unexposed portions of the gelatin layer are washed away, leaving the raised portions 19 upon the plate 15. The plate 15 is then dried and may then be sealed in the tube for generating the signals above described.

Alternatively, a solution of bitumin of judea dissolved in oil or lavender may be flowed across the plate to provide the photo-chemical variable layer. The action of light makes the bitumin insoluble so that after exposing the picture through a half-tone screen upon the layer of bitumin on the metal plate, the plate may be developed in oil of lavender, which removes the unexposed bitumin. The plate is then dried and may be used, as indicated above, for the chrome gelatin plate above described.

It will be appreciated, of course, that the metal plate may be of some other metal other than aluminum, such as copper or nickel or tantalum, or any other metal whose secondary emission properties are different than the properties of the picture elements in relief upon the plate.

It will thus be appreciated that applicants' new plate provides a simpler plate for use in a cathode ray scanner and that the combination of applicants' plate and the cathode ray scanner described above results in an improved method of transmitting the electro-optical representations.

Having described our invention, what we claim is:

1. A cathode ray tube comprising an envelope, means for producing a focused beam of electrons within the envelope, means for deflecting the produced focused beam of electrons in two mutually perpendicular directions, a planar electrode of predetermined specific secondary electron emissivity, isolated minute particles of a material having a specific secondary electron emissivity different from that of the electrode positioned on the electrode and forming a half-

tone picture, the area of said particles corresponding to the density of the elemental areas of the half-tone picture, said electrode being positioned to be impacted by the deflected beam of electrons, and means to collect secondary electrons emitted from the particles and the electrode under the impact of the deflected focused beam, said beam producing means, said secondary electron collecting means and said electrode being within said envelope. 5

2. In combination, means for producing a focused beam of electrons, a target electrode of predetermined specific secondary electron emissivity, a plurality of elemental particles of a material having a different specific secondary electron emissivity than that of the electrode, said particles being positioned on the target electrode to form elemental areas of a half-tone picture, the area of said particles corresponding to the density of the elemental areas of the half-tone 20 picture, means for deflecting the focused beam to scan substantially the entire area of the target and all of the plurality of particles to cause secondary electrons to be emitted from the target and plurality of particles, and means to collect 25 the emitted secondary electrons, beam producing means, said secondary electron collecting said means and said electrode being within said envelope. 10

3. A cathode ray tube comprising an envelope, 30 means for producing a focused beam of electrons within the envelope, means for deflecting the produced focused beam of electrons in two mutually perpendicular directions, a planar metallic electrode of predetermined specific secondary 35 electron emissivity, isolated minute particles of a material having a specific secondary electron emissivity different from that of the electrode positioned on the electrode and forming a half-tone picture, the area of said particles corre- 40 sponding to the density of the elemental areas of the half-tone picture, said electrode being positioned to be impacted by the deflected beam of electrons, and electrode means to collect sec- 45 ondary electrons emitted from the particles and the electrode under the impact of the deflected focused beam, said beam producing means, said electrode means and said metallic electrode being positioned within said envelope. 35

4. An electronic device comprising an envelope, 50 an electron gun for producing a beam of focused electrons positioned within the envelope, a metallic target electrode of predetermined specific sec- 55 ondary electron emissivity positioned within the envelope in register with the electron gun, a half- 55 tone picture formed of isolated particles of ma- 60 terial having a specific secondary electron emis- 65 sivity different from that of the target electrode positioned upon the target electrode, the areas of said particles corresponding to the density of the elemental areas of the half-tone picture, means within the envelope intermediate the gun and said target electrode for scanning said target electrode and the half-tone picture thereon by the focused beam of electrons, and electrode 70 means within the envelope intermediate the tar- 70 get and the scanning means for collecting sec- 75 ondary electrons emitted from the half-tone pic- 80 ture and the target electrode under the impact of the scanning focused beam of electrons. 70
